CLAIM

The ornamental design for a firearm support, as shown and described.

DESCRIPTION

FIG. 1 is an isometric view of an embodiment of a firearm support.

FIG. 2 is a left side view thereof.

FIG. 3 is a right side view thereof.

FIG. 4 is a front elevational view thereof.

FIG. 5 is a rear elevational view thereof.

FIG. 6 is a top plan view thereof; and,

FIG. 7 is a bottom view thereof.

The broken lines in the drawings form no part of the claimed design.
